Primary Examiner — Mark Goodwin(74) *Attorney, Agent, or Firm* — Alleman Hall McCoy Russell & Tuttle LLP(57) **CLAIM**

The ornamental design for a reachstacker, as shown and described.

DESCRIPTION

FIG. 1 is a front view of a design for a reachstacker according to the present disclosure.

FIG. 2 is a back view of the reachstacker of FIG. 1.

FIG. 3 is a right view of the reachstacker of FIG. 1.

FIG. 4 is a left view of the reachstacker of FIG. 1.

FIG. 5 is a top view of the reachstacker of FIG. 1.

FIG. 6 is a front perspective view of the reachstacker of FIG. 1; and,

FIG. 7 is a back perspective view of the reachstacker of FIG. 1.

The solid lines in FIGS. 1-7 illustrate a reachstacker according to the present disclosure.

A bottom view is not shown because there are no claimed features on the bottom view other than those features included in the views provided.
